UNITED STATES PATENT OFFICE.

FRANK A. HOUCK, OF KETCHIKAN, TERRITORY OF ALASKA.

POWER-GURDY.

1,384,895.

Specification of Letters Patent.

Patented July 19, 1921.

Application filed February 3, 1920. Serial No. 355,940.

To all whom it may concern:

Be it known that I, FRANK ALBERT HOUCK, a citizen of the United States of America, and resident of the city of Ketchikan, Territory of Alaska, have invented certain new and useful Improvements in Power-Gurdies, of which the following is a specification.

My invention relates to gurdies and consists of a gurdy so designed as to be applicable to power driven boats, and to be turned by power taken from the propeller shaft.

The object of my invention is to provide a gurdy of such design that it may be conveniently installed upon power driven boats in such a way as to be driven from the propeller shaft and to provide such driving means of a character that the operation of the gurdy may be conveniently controlled by the man who is attending to the lines.

In the accompanying drawings I have shown my invention in a type of construction well adapted for this purpose and which I now prefer to use.

The features of this device which I believe to be novel and which I wish to patent will be first described and then particularly pointed out in the claims.

Figure 1 is a longitudinal section through the rear portion of a boat, showing the manner of installing my device and its construction.

Fig. 2 is a section taken in a plane transversely of the boat, just rearward of the friction driving mechanism, and looking forwardly, or toward the bow.

Fig. 3 is a similar section taken on the same plane but looking rearwardly, or toward the stern.

Fig. 4 is a top view of the holding head and its associated parts.

In the drawings 1 represents the propeller shaft. This, at the rear-end of the boat goes through a portion 2 of the frame of the boat, which is ordinarily called the scag. The forward end of this, which is the rearmost point at which the propeller shaft is accessible within the boat, is located some distance forwardly of the point where it is desired to locate the gurdy.

The holding head consists of a pulley or drum 3, and the two guide pulleys 30 and 31. These are mounted in the relative position shown in Fig. 4 and are installed upon the rear of the boat close to the stern. The

guide pulley 30 is located where the line may be conveniently run thereon as it is being hauled in and so as to direct the line on leaving the same to the holding head 3.

The guide pulleys 30 and 31 are mounted upon a plate, 45, which is of rolled metal and mounted to swing upon the hub 46 of the hauling head. This plate may be swung so as to place the outbound guide pulley 30 well over the outer edge of the rail, or inward so as to bring everything within the rail's outer edge, so that it will not be engaged by a dock when lying alongside. A pin 47 serves to secure this plate in either position being adapted to engage with either of two sockets 48 located at the inner and outer edges of the rail.

The holding head 3 is designed to apply its power to haul the line by means of frictional engagement of the line therewith. For this purpose it may be provided with a groove into which the line may drop and thus be frictionally grasped by the side walls thereof. The guide pulleys 30 and 31 are so placed as to give as large an arc of contact of the line with the head 3 as may be conveniently secured.

The head 3 is connected by the mechanism illustrated in the drawings with the propeller shaft so as to be turned thereby. The line, after passing over the holding head is coiled either upon the deck or in a box or other container.

The shaft 34 of the holding head is journaled in a casting 33 which is secured on the rail, the shaft extending downward through the deck of the boat and at its lower end has thereon a bevel gear 35, which meshes with a bevel gear 42 which is secured to one section 40 of a telescopic shaft. The other section of the shaft is herein shown as being a pipe 4 into which the shaft 40 enters, whereby they may have relative lengthwise movement. The adjacent ends of the two shafts 34 and 40 are journaled within a frame member or casting, as 43, which may be secured to the side of the boat or to any convenient support.

It is desirable that the driving mechanism, which connects the holding head with the propeller shaft, contain a resilient or yielding member, so that if the line, while being hauled in, should in any manner become suddenly checked, the holding head will be stopped or momentarily checked and the line will not become broken. For this

reason and also for convenience in adjusting the transmission mechanism to boats of differing size and design, the telescopic shaft section has been employed. To secure the yielding action I employ a helical spring 41, which surrounds both the telescopic shaft sections and has one end secured to each of these shaft sections.

The telescopic shaft is connected by a universal joint 44 with a shaft 5 which is journaled in a yoke 50, pivoted at 51 and adapted to swing in a fore-and-aft direction. Mounted upon this shaft is a small friction gear or pinion 6, this being connected with the shaft by a key and keyway, or by any other accepted means which will permit shifting of the pinion lengthwise of the shaft while maintaining the two so as to turn together. For shifting, the common expedient of a grooved collar 60 upon the pinion and a control lever 61 is employed. This lever 61 is pivoted at 62 upon the front side of a bulkhead 10. Adjacent the pivot it is laterally bent and passes through the bulkhead, having its operating end outside the bulkhead convenient to the cock-pit 11, in which the operator works.

Coöperating with the friction pinion 6 is a friction disk 63 which is mounted upon a shaft, as 7, which extends fore and aft and which is connected with a jack shaft 70 by a universal coupling 71. Upon the forward end of the jack shaft 70 is a spur gear 8. Upon the propeller shaft is a spur pinion 80. These are connected by an intermediate pinion 81 which is provided with a grooved collar 82 by means of which the pinion may be shifted so as to slide it lengthwise out of engagement with one of these gears. The pinion 80 and the gear 8 are placed out of alinement enough so that the pinion 81, which is of a breadth of face equal to the combined faces of the pinion 80 and gear 8, may be slid axially enough to disengage it from one of these while maintaining engagement with the other, and may, in proper position, engage both.

Any convenient means for shifting this pinion may be employed. That shown consists of a rod 85 which at its forward end is laterally bent to engage with a collar or ring 83 which fits between the flanges of the grooved hub 82 of pinion 81. This rod extends to the cock-pit and has a handle end 87 which may be secured in adjusted position, as by teeth on the rod and a holding dog 88. Any other suitable means may be employed for holding the transmission gears just described in engagement.

Upon the rear end of the shaft 7 is a friction disk 63 which is adapted to be engaged by the friction pinion 6. This pinion, being

mounted in the swinging yoke 50, may be caused to engage and disengage with the driving disk 63 as desired. To control this I have shown a rod 52 which passes through the bulkhead 10 and is connected with a bell crank controlling lever 53. A spring, as 54, is employed for normally holding the friction pinion 6 out of engagement with the disk 63.

When it is not desired to use the gurdy, the intermediate driving pinion 51 is shifted so as to be disengaged from the driving pinion 80. The entire mechanism is thus thrown out of action. By employing a friction driving device of such character as the disk 63 and pinion 6, and locating this so that its normal tendency is to be disengaged, the operator can conveniently control the action of the gurdy by holding the pinion in engagement with the disk whenever he wants to haul in upon a line. By employing the resilient or yielding transmission member represented by the spring 41, sudden shocks which would over-strain the line and break it may be avoided. The same results to a certain extent may be secured by applying the friction driving lightly. However, the use of a yielding member such as the spring 41 is very desirable in addition to the friction driving clutch.

In using the gurdy the line is placed over the outer guide pulley 30 about the holding head 3 and the guide pulley 31. It thus has a sufficient engagement with the holding head 3 to enable the latter to pull in the line. The strength of the pull which may be thus communicated to the line will, of course, depend somewhat upon the pull which is given to the line in removing it from the gurdy. As these line guiding and holding members are supported only from one side the line may be conveniently passed about them.

What I claim as my invention is:

1. In a power gurdy, a line-hauling wheel journaled at the rail, a frame pivotally mounted upon the rail and line guiding pulleys carried by the swinging end of said frame.

2. In a power gurdy, a horizontally positioned line hauling wheel journaled at the inner side of the boat's rail, a frame pivoting upon the same shaft as the wheel, line guiding pulleys carried by the swinging end of the said frame and adapted when the frame is swung outwardly to conduct the line over the rail, and means for locking said frame in outer and inner positions.

Signed at Seattle, King county, Washington, this 29th day of January, 1920.

FRANK A. HOUCK.
